UNITED STATES PATENT OFFICE.

SAMUEL EVERETT DOANE, OF CLEVELAND, OHIO, ASSIGNOR TO THE FOSTORIA BULB AND BOTTLE COMPANY, OF FOSTORIA, OHIO, A CORPORATION OF OHIO.

GLOBE FOR ARC-LAMPS.

SPECIFICATION forming part of Letters Patent No. 762,029, dated June 7, 1904.

Application filed June 24, 1903. Serial No. 162,841. (No model.)

To all whom it may concern:

Be it known that I, SAMUEL EVERETT DOANE, a citizen of the United States, residing at Cleveland, in the county of Cuyahoga and State of Ohio, have invented a certain new and useful Improvement in Globes for Arc-Lamps, of which the following is a full, clear, and exact description, reference being had to the accompanying drawings.

- 10 In inclosed-arc lamps it has been found essential to employ an inner globe of comparatively small size surrounding the carbons and containing the burned-out air. In order that there shall be no circulation of fresh air 15 through the globe, it is necessary that the ends of the globe fit the coöperating portions of the lamp snugly; but as the globe from its proximity to the arc is subjected to considerable heat its longitudinal expansion prevents it being clamped tightly. Therefore it has been customary in employment of inner globes with inclosed-arc lamps to secure the globe at the lower end in a more or less yielding manner and at the upper end to allow it to abut against 20 a suitable head. Such head is frequently made of metal and has up-and-down play and rests on the upper end of the globe. Now in the operation of the lamp and in the removal and replacement of the globes for trimming the 25 lamp the globes are frequently broken, and the aggregate expense of operating the lamp is thus considerably increased. I have discovered that the breakage is caused to a very large degree by the mechanical impingement 30 of the extreme end of the globe with its coöperating head, both by the lamp itself, due to the jerks when the arc flashes or sputters, and by the operator removing or replacing the globe.
- 35 The purpose of the present invention is to provide a globe in which such breakage shall be prevented or reduced to a minimum.

The ends of the globes heretofore used are usually ground to make a substantially tight joint with the coöperating head, and thus the blow comes upon the weakest part of the globe, where the skin of the glass has been removed by the grinding, and starts a crack, which trav-

els along the globe. I provide for the globe a ring-shaped cap, which contacts with its outer surface some distance beyond the extreme end of the globe and then extends toward the end of the globe and across the end without contacting therewith. The cap makes a substantially tight joint with the usual head 55 for the globe, and when this cap contacts with such head the blow is carried by the cap to the outer surface of the globe, where it is delivered in a glancing manner and against a surface fully protected by the skin of the glass. 60 I fill in the space between the ring-shaped cap and the extreme end of the globe with some suitable cement, preferably an elastic cement, which securely fastens the ring to the globe. I have found by thorough test that such a cap 65 fully protects the end of the globe and practically does away with the breakage. The cap makes a connection with the head as good as or better than the ground-glass edge.

The drawings clearly illustrate my invention.

Figure 1 is a side elevation of the lower portion of an inclosed-arc lamp having my globe with the cap applied to the upper end thereof. Fig. 2 is a vertical section through the upper 75 portion of the globe and the coöperating head.

Referring to the parts by letters, A represents the frame of the lamp, B the upper carbon, and C the lower carbon. The lower carbon is suitably held by the lower-carbon 80 holder D, which may also hold the lower end of the globe in any suitable manner. These details may be of any form desired.

The globe itself is designated E. At its upper end it is designed to make close contact 85 with the head F, which surrounds the upper carbon and is loosely guided by the hook α' of the frame member α and rests by gravity on the upper end of the globe. The ring cap, which I have shown on the upper end of the 90 globe, is designated G and is preferably made of brass and lies on the outside of the globe. Its upper surface g is preferably flat to make a snug contact with the head F. From the outer edge of this surface g the ring extends 95 downward, as at g' , preferably in a flaring

manner, but not flaring so much as the globe, so that the cap contacts first with the globe some distance below the extreme end thereof. Thus from the lower edge of the metal ring 5 all the way up it is out of contact with the globe. The flat portion g of the ring is some distance above the extreme edge of the globe, and this flat portion extends inward somewhat farther than the inner surface of the globe.

10 It is customary to provide the head F with a downward bell-like projection f , from which leads the air-passage f' , and to protect the globe when being removed or replaced from contacting with this projection I form a short 15 downward flange g^2 on the inner edge of the protecting-ring. Between the ring and globe I place suitable cement H, preferably one of the well-known elastic cements, to permanently secure the cap to the globe and make 20 an air-tight connection between them.

Having described my invention, I claim—

1. A glass globe open at its end and protected by a ring which is permanently cemented to it out of contact with the extreme end 25 of the globe, but contacts with the side surface of the globe and extends beyond the end thereof, substantially as described.

2. A glass globe open at its end and protected by a ring-shaped cap which is permanently secured to it out of contact with the extreme end of the globe, but contacts with the side surface of the globe and extends across the extreme end thereof, substantially 30 as described.

3. A glass globe open at its end and protected by a ring-shaped cap which is out of contact with the extreme end of the globe but contacts with the outer side of the globe and extends across the extreme end, substantially 35 as described.

4. The combination, with an inclosed-arc

lamp, of an inner globe therefor, a protecting-cap permanently carried by said globe, a member of the lamp with which said cap is adapted to contact, said cap being out of contact with the extreme end of the globe but contacting with the outer surface thereof, and filling making an air-tight connection between the cap and the globe, substantially as described. 45

5. The combination, with a glass globe open 50 at its end, of a protecting-cap contacting with the outer surface of the globe some distance from the extreme end, said cap continuing out of contact with the globe beyond the end and then having a portion extending inwardly 55 across the end of the globe but out of contact therewith, substantially as described.

6. The combination, with a glass globe open 60 at its end, of a protecting-cap contacting with the outer surface of the globe some distance 65 from the extreme end, said cap continuing out of contact with the globe beyond the end and then having a portion extending inwardly across the end of the globe but out of contact therewith, and then having an inwardly-extending flange out of contact with the globe, and cement between the cap and the globe, substantially as described.

7. A glass globe for an arc-lamp having an open end and a ring-shaped cap for protecting 70 said end, said cap being secured to the globe out of contact with the extreme end thereof and passing across said extreme end and having at its innermost periphery a flange extending toward the interior of the globe, substantially 75 as described.

In testimony whereof I hereunto affix my signature in the presence of two witnesses.

SAMUEL EVERETT DOANE.
